UNITED STATES PATENT OFFICE.

JOHN B. KEATING, OF PIEDMONT, CALIFORNIA.

SUBMERSIBLE PUMP AND THE LIKE.

Application filed April 4, 1921. Serial No. 458,304.

To all whom it may concern:

Be it known that I, JOHN B. KEATING, a citizen of the United States, and resident of Piedmont, Alameda County, California, have invented new and useful Improvements in Submersible Pumps and the like, of which the following is a specification.

My invention has for its particular object hydraulic mechanism, as a pump, in combination with a driving motor or generator and which may be adjusted to any position as within a well for the purpose of pumping from such well the water which flows in from the surrounding strata. It is particularly adapted to pumping deep casing wells, where the casing perforations are below the pump, although it is also suited to other wells not cased or wells where the casing is perforated above the pump, and in such cases is preferably to be provided with a suitable casing or discharge pipe connected to the said pump and immediately surrounding the motor.

In pumps of this general type it has heretofore been customary to extend a vertical operating shaft from said pump upward through the casing to a suitable motor or driving means located above the well or at least above that portion of the well subject to water overflow during the operation of the pump, or when it is stopped and water rises around the pumping end of the unit. Such construction is expensive, both as to first installation and operation and these disadvantages increase as the depth of the well or distance through which the water is to be pumped increases. Moreover, to remove such pump from the well, to repair and replace, becomes a costly process and the maintenance of lubrication to the bearings, of which a number are necessary on account of the long driving shaft, is expensive and inefficient and requires special attention in operation and expensive additional supporting structure. In such bearings lubrication is not infrequently destroyed and they become flooded with water; whereas in the pump and motor of my invention the bearings are kept free from contamination with pressure water and adequate lubrication is maintained through a counterbalancing or excess pressure behind the oil feed so that no leakage of water into the motor bearings occurs. Moreover, the motor is enclosed in a sealed compartment of smooth exterior from which the water

is kept excluded by internal pressure, thus securing at all times a free running, submerged pump of minimum weight, requiring a minimum of power, more easily accessible for repairs and replacement and cheaper in first cost and maintenance.

By referring to the accompanying drawings my invention will be made clear.

Figure 1 is a vertical cross section through a pumping unit of my invention, as positioned within a well casing and showing one form of sealing means.

Fig. 2 is similar to Fig. 1 with certain of the portions shown in full lines and with a diagrammatic showing of the oil feeding system and the delivery pipe.

Fig. 3 is a fragmentary view of certain of the parts of Fig. 2 wherein I employ a separate discharge column in place of the sealing means of Figs. 1 and 2.

Fig. 4 is a sectional view of the upper part of the motor casing of Fig. 1 showing a portion of the casing and the suspension member and with pipe and electrical connections passed into the motor casing through sealing means.

Throughout the figures similar numerals refer to identical parts.

The casing tube of the well is indicated by the numeral 1 which extends within gravel or other strata containing water, oil or liquid to be pumped from the well and in which, when the pump is idle, it is understood the liquid rises to the water table level indicated by the numeral 2. At 3 is shown the ground surface and at 4 the delivery pipe from which the water pumped may flow to any desired point of delivery. A suitable suspension member 6 and support 7 carry the weight of the parts. The suspension member 6 carries on its lower end the motor casing 9 which is hermetically sealed. Between the pump casing 11 and motor 9 is a shaft bearing 12 and the packing 13, thereby sealing the joint between the pump and the motor casing against water ingress under ordinary conditions. Between the bearing 12 and gland means 14 I form the chamber 16 into which flows any water that leaks from the pressure side of the pump runner 17 through the sleeve bearing 12 and which water will be discharged therefrom freely through pipe or channel 18, back to the suction side of the pump at 21 or there may be substituted a hollow shaft or any pipe or conduit connec-

tion from the chamber 16 to a point of lower pressure as the suction side of the pump. In this way it will be seen that the tendency for any pressure water getting into the 5 motor casing 9 during the operation of the pump is reduced to a minimum as the chamber 16 is kept drained. If the pump is stopped and the air leaks out of the chamber 16 the water will rise therein and tend 10 to find its way into the motor casing on account of the static pressure that will then exist due to the higher level of the water table at 2. It is clear that any flooding of the motor casing 9 will be fatal to successful 15 operation and therefore to insure the operation at any and all times it is essential to keep the said casing and bearings free from water. This I accomplish as explained below.

20 In the operation of a submerged pump such as I have here shown I may employ the space between the motor casing 9, pump casing 11 and well casing 1 as the discharge column of the pump as shown in Figs. 1, 2, 25 or discharge column 8 may be employed separate from the well casing as in Fig. 3, in either case the discharge will take place in the direction of the arrows 22 and be delivered through the outlet 4, at such times 30 reducing the water level on the suction side within the casing 1 to some point such for example as that indicated by the line 23, Fig. 1. During pumping the water will be delivered normally through the outlet 4 under 35 some discharge pressure determined by local conditions and the characteristics of the pump. The excess pressure in the delivery column over that in the suction column of the casing makes necessary a seal 40 between the two which I accomplish either by a separate discharge pipe to the surface as 8, Fig. 3; or by the cup leather 27, within which there may be an expansion ring member 28 to insure its contact with the 45 walls of the casing, see Fig. 2, or the said expansion member may consist of an air expansion tube having an air supply connection at 30; or an inflatable tube 31 with an air connection at 32 may be employed as in 50 Fig. 1. In either case the discharge column will be sealed from the suction column either by separate discharge pipe or by the expansion of the member 27 or 31 between the pump casing 11 and the well casing 1.

55 While I have shown a tubular or pipe member 6, from which is suspended the motor casing 9, and within which are carried the electric conductors 34, 35 and the oil pipe 37 it will be obvious that these may 60 be separately conveyed to the motor casing 9 and the latter may be suspended with a cable or in any other well known way. In the construction I have shown these conductors and oil pipe are adapted to pass 65 through sealing means 10, preferably lo-

cated at the top of the motor casing 9. The oil pipe 37 is adapted to be passed in any well known way through the motor casing 9 to its delivery end, 38 Fig. 1. The upper end of the pipe 37 is connected to a 70 reservoir 42 and is fitted with a control valve 43 whereby oil may be fed from a point above the ground surface 3 to the interior of the submerged motor casing 9, see Fig. 1.

I have also shown an air pipe 44 which is connected through a suitable cover 46 on the oil reservoir 42 from a source of compressed air or gas shown diagrammatically at 45. A sight gauge at 47 on the reservoir 80 42 indicates the oil level at all times and a pressure gauge at 48 indicates the pressure in the motor casing 9.

To insure against the formation of an explosive mixture within the motor casing 85 9, a neutral gas may be supplied from the compressor 45 as an initial charge in the motor casing 9. This neutral gas may with advantage be air from which the oxygen has been burnt and therefore consist of nitrogen; or of carbonic acid gas, or any other inert gas may be employed not detrimental to the apparatus, and in such case I recommend the primary abstraction of air from the casing 9. This may be done by blowing 90 the air from the casing through a separate pipe 51 and valve 52.

The assembled pump and motor are first let down into the well casing 1 by the suspension member 6 to the desired depth, and if the depth is sufficient to make it necessary, air or inert gas is forced into the motor casing 9 as from the compressor 45 through valves 49 and 50 and pipe 37, so that an internal pressure in the casing 9 is indicated on the gauge 48 sufficient to more than compensate for any contraction of the normal air within 9 due to the external water pressure on account of the elevation of the water table 2 above the said casing 9. This will prevent the ingress of any possible water into the pump casing. A small quantity of oil is permitted to flow through the pipe to the outlet 38, lubricating the bearings and packings and oil-sealing the motor housing 9 between the outside liquid and the inside gas; that is, the leakage through the said gland, if any, will be a very gradual outflow of oil which is constantly replenished from an external source. Lubrication is thus established and thereafter maintained during the pump operation. The water table drops within the casing to the line 23 and the water is delivered through the outlet 4 to the reservoir 5. The pressure conditions within the motor casing 9 are indicated on the gauge 48 and this is balanced by the column of oil rising to 47. The running condition will therefore at all times be one of perfect lubrication of the bearings 130

insured by a slow leakage of oil therethrough.

If the pump is to be shut down for any considerable time oil leakage may be prevented by closing the valve 43.

I am well aware of the explosive nature of hydrocarbon gases mixed with air and of the sparking possibilities in and about electrical apparatus and that in some cases crude oil from which the lighter hydrocarbons have not been entirely extracted may be employed as a lubricant for the pump, hence the necessity of employing a neutral gas within the pump case.

15 In practicing my invention it is to be noted that I employ a low pressure at the suction side of the pump and a discharge pressure at the outlet of the pump and a pressure in the motor casing equal to or in excess of suction pressure whether above or below that of the atmosphere, by which latter the entry into the motor casing or bearings of any other fluid than oil as set forth is prevented.

20 Also I prefer to introduce 25 through the motor casing and under the said equal or higher pressure a lubricant for the bearings of the moving parts. In maintaining this equal or higher pressure in the motor casing, lubrication may be secured in other ways and I may introduce into the motor casing a fluid in which air may be insoluble and which, lying between the zone of air or gas pressure in the motor housing and the liquid outside of the motor

30 housing will act as an impervious strata to the air or gas and prevent the absorption of the latter in the water and therefore act as a seal to maintain the said air or gas intact within the motor chamber and consequently retain the motor at all times under proper running condition.

It will also now be seen that instead of introducing air or gas into the motor chamber through the pipe 37, it may be introduced through the pipe 51 either before or after the oil from 42 is fed therethrough, and I desire to be understood as claiming all such variations.

While I have described my invention as particularly adapted to a pumping unit it is to be noted that it may also be employed in hydraulic turbines driving generators or in other submerged machinery and hydraulic devices generally and I desire to be understood as claiming all such variations.

In speaking of suction pressure I am well aware that this may be negative, that is, below the atmospheric pressure and in such case is to be considered as referred to the absolute zero of pressure.

I claim:

1. In a vertical pumping unit, a motor, an annular casing of smooth exterior, a motor within said casing and a shaft extending 65 through a gland in said casing, an impeller

adapted to be driven by said shaft, an oil pipe extending from a remote point to the lower part of the interior of said casing and adapted to deliver oil to said gland and means adapted to establish an oil pressure 70 through said pipe.

2. In a vertical pumping unit, a motor inclosed in a circular casing of smooth exterior and having a shaft and a gland in said casing, an impeller operable by said 75 shaft, an oil pipe extending from a remote point to the lower part of the interior of said casing and adapted to deliver oil to said gland, and means adapted to establish an oil pressure through said pipe, in combination with a housing for said impeller provided with inlet and outlet passages, the last named passage constructed and adapted to direct water pumped by said impeller over the smooth exterior 85 of said casing.

3. In a vertical pumping unit, a motor inclosed in a circular casing of smooth exterior, a motor shaft and a gland in said casing, an impeller operable by said shaft, an oil pipe extending from a remote point to the lower part of the interior of said casing and adapted to deliver oil to said gland, and means adapted to establish an oil pressure 90 through said pipe, in combination with a housing for said impeller provided with inlet and outlet passages, the last named passage constructed and adapted to direct water pumped by said impeller over the smooth exterior of said casing, and a tubular 100 suspension member constructed and adapted to inclose power wires to said motor and to inclose said oil pipe.

4. In a vertical pumping unit, a motor and a gas tight casing inclosing said motor, a shaft driven by said motor and passing through packing means in said casing and adapted to drive an impeller, a pipe passing through and terminating in the lower inside of said casing and an oil reservoir adapted 110 to feed lubricant through said pipe, and means constructed and adapted to establish a gas pressure in said casing.

5. In a vertical pumping unit, a motor and a gas tight casing inclosing said motor, 115 a shaft driven by said motor and passing through packing means in said casing and adapted to drive an impeller, a pipe passing through and terminating in the lower inside of said casing and an oil reservoir feed- 120 ing lubricant through said pipe under pressure, means including a second pipe by which a predetermined gas pressure may be established and maintained in said casing, in combination with a housing about said 125 impeller and provided with inlet and outlet passages, the last named passage constructed and adapted to direct water pumped by said impeller over the smooth exterior of said casing.

6. In a vertical pumping unit, a motor and a gas tight casing inclosing said motor, a shaft driven by said motor and passing through packing means in said casing and adapted to drive an impeller, a pipe passing through and terminating in the lower inside of said casing and an oil reservoir feeding a fluid of low gas solubility through said pipe under pressure, means including a second pipe by which a predetermined gas pressure may be established and maintained in said casing, in combination with a housing about said impeller and provided with inlet and outlet passages, the last named passage constructed and adapted to direct water pumped by said impeller over the smooth exterior of said casing, and a tubular suspension member constructed and adapted to inclose power wires to said motor and to inclose said pipes.

7. In a vertical pumping unit, a motor and a gas tight casing inclosing said motor, a shaft driven by said motor and passing through packing means in said casing and adapted to drive an impeller, a pipe passing through and terminating in the lower inside of said casing and an oil reservoir feeding lubricant through said pipe under pressure, means including a second pipe by which a predetermined gas pressure may be established and maintained in said casing, in combination with a housing about said impeller and provided with inlet and outlet passage, the last named passage constructed and adapted to direct water pumped by said impeller over the smooth exterior of said casing, and a tubular suspension member constructed and adapted to inclose power wires to said motor and to inclose said pipes and sealing means around said wires and said pipes.

JOHN B. KEATING.
